(57) **CLAIM**

The ornamental design for an electric machine with drive circuit as shown and described.

DESCRIPTION

FIG. 1 is a front perspective view from the left side and above of an embodiment of electric machine with drive circuit showing my new design;

FIG. 2 is a rear perspective view from the left side and above of the electric machine with drive circuit of FIG. 1;

FIG. 3 is a right side view of the electric machine with drive circuit of FIG. 1;

FIG. 4 is a front view of the electric machine with drive circuit of FIG. 1;

FIG. 5 is a rear view of the electric machine with drive circuit of FIG. 1;

FIG. 6 is a plan view of the electric machine with drive circuit of FIG. 1;

FIG. 7 is a bottom view of the electric machine with drive circuit of FIG. 1;

FIG. 8 is a front perspective view from the left side and above of an alternative embodiment of electric machine with drive circuit showing my new design;

FIG. 9 is a rear perspective view from the left side and above of the electric machine with drive circuit of FIG. 8;

FIG. 10 is a right side view of the electric machine with drive circuit of FIG. 8;

FIG. 11 is a front view of the electric machine with drive circuit of FIG. 8;

FIG. 12 is a rear view of the electric machine with drive circuit of FIG. 8;

FIG. 13 is a plan view of the electric machine with drive circuit of FIG. 8; and,

FIG. 14 is a bottom view of the electric machine with drive circuit of FIG. 8.

The broken lines shown represent portions of the electric machine with drive circuit therefor that form no part of the claimed design.
